UNITED STATES PATENT OFFICE.

WILLIAM KIRKWOOD, OF GUELPH, ONTARIO, CANADA.

SECTIONAL WATER-HEATER.

SPECIFICATION forming part of Letters Patent No. 388,418, dated August 28, 1888.

Application filed December 15, 1887. Serial No. 237,957. (No model.)

To all whom it may concern:

Be it known that I, WILLIAM KIRKWOOD, of the city of Guelph, in the county of Wellington, in the Province of Ontario, Canada, 5 steam-fitter, have invented certain new and useful Improvements in Sectional Water-Heaters, of which the following is a specification.

The object of the invention is to design a 10 cheaply-constructed sectional water-heater, in which a perfect circulation is maintained through independent tubes arranged so that they will be surrounded by the heated gases arising from the combustion-chamber of the 15 furnace; and it consists, essentially, of two vertical chambers arranged parallel with each other and suitably partitioned, horizontal tubes being connected to the walls of and arranged to connect with the interior of one chamber 20 which is bridged by horizontal tubes of a smaller diameter connected to the walls of and communicating with the interior of the other chamber, the said tubes extending into the tubes connected to the wall of the former chamber, so that the fluid entering the latter will 25 flow through the larger tubes and find its way through the smaller tubes into the other chamber, the whole being arranged in detail, substantially as hereinafter more particularly explained.

The drawing is a sectional perspective view of my improved water-heater.

In the drawing, A is the feed-water pipe, which communicates with a chamber, B'. This 35 chamber is formed between the walls *a* and *b*, which extend the full height and width of the heater.

d is a vertical wall or partition located between and corresponding with the walls *a* and 40 *b*, so as to make a division and form the two parallel chambers B C.

D represents a series of horizontal tubes closed at one end and each screwed or otherwise secured to the inner walls, *a*, so that the 45 interior of all the pipes will communicate with the chamber B.

E represents a series of tubes smaller in diameter than the tubes *D* and open at both ends. Each of these tubes *E* extends into one of the 50 tubes *D*, and is screwed or otherwise secured into the wall *d*, so that it will extend across the

chamber B into the tubes *D* and form a connection between the interior of the chamber C and the interior of each of the tubes *D*.

In order to secure complete circulation 55 through the heater when it is to be used for warming water, I form horizontal partitions across the chambers B and C, the effect of which partitions will be understood when I explain the operation of my heater. The wall *d* might 60 extend the full length of the walls *a* and *b*; but in the drawing I have shown it commencing at a point just below the lower row of tubes *D*, and at that point have formed a horizontal partition *e*, extending across the heater and closing 65 the bottom of the chamber B.

I do not claim anything peculiar in the arrangement of the furnace; but I may say that F represents the grates of the furnace and G its door. H and I are two pipes arranged to 70 fit around the wall of the furnace and connected together at one end, while their other ends are connected to the walls *a* and communicate with the interior of the chamber C, as shown. The water which enters through the 75 pipe A will naturally flow through the pipes H and I and ascend to the partition *f*, extending across and dividing the chamber C. As the three lower rows of the tubes *E* communicate with this lower portion of the chamber C, 80 the water will naturally flow through them and find its way out of their opposite ends into the tubes *D* and through them into the chamber B, and by following the course indicated by arrow will return through the next rows of 85 tubes *D* and *E* back into the chamber C above the partition *f*, and then back through the tubes *E* *D* into the chamber B above the partition *g*, and so on until it reaches the dome J, from 90 which it is carried in the usual way.

In the illustration of my boiler I divide the chambers B C, so that the tubes *D* *E* shall be in sets of three; but I do not confine myself to any particular number of divisions, as the number may be altered to suit the opinion of 95 the particular manufacturer making the boiler.

In order that the tubes *D* may be readily cleaned, I provide a door, K, which may be readily opened to expose all the tubes, which may thus be easily cleaned of any deposit left 100 on them by the heated gases ascending from the furnace.

It will be observed that by my arrangement of the tubes the course of water is alternated—that is, in the lower group the water enters the tubes E and passes out the tubes D, while in the next group the water enters the tubes D and passes out the tubes E, and so on. This is important.

What I claim as my invention is—

1. Two vertical chambers arranged parallel with each other and suitably partitioned, horizontal tubes being connected to the walls of and arranged in groups, as described, to connect with the interior of one chamber, which is bridged by horizontal tubes of a smaller diameter connected to the walls of and communicating with the interior of the other chamber, the said tubes extending into the tubes connected to the wall of the former chamber, so that fluid entering the latter will flow through the larger tubes and find its way through the smaller tubes into the other chamber in one group and vice versa in the next group, substantially as and for the purpose specified.
2. Two vertical chambers arranged parallel with each other and suitably partitioned, horizontal tubes being connected to the walls of and arranged in groups, as described, to connect with the interior of one chamber, which is bridged by horizontal tubes of a smaller diameter connected to the walls of and communicating with the interior of the other chamber, the said tubes extending into the tubes connected to the wall of the former chamber, so that fluid entering the latter will flow through the larger tubes and find its way through the smaller tubes into the other chamber in one group and vice versa in the next group, substantially as and for the purpose specified.

ameter connected to the walls of and communicating with the interior of the other chamber, the said tubes extending into the tubes connected to the wall of the former chamber, so that fluid entering the latter will flow through the larger tubes and find its way through the smaller tubes into the other chamber in one group and vice versa in the next group, in combination with the dome J, into which the said chambers communicate, substantially as and for the purposes specified.

3. The tubes D, closed at one end and connected at their opposite open end to the wall a, and containing smaller tubes, E, open at both ends, but connected to the walls d at one end, so that the chambers B C will be connected through the tubes specified, in combination with horizontal partitions formed across the chambers B C, and alternating, as shown, and the pipes H I, arranged beneath the lower partition around the furnace, substantially as and for the purpose specified.

Guelph, November 22, 1887.

WILLIAM KIRKWOOD.
